UNITED STATES PATENT OFFICE

2,377,931

CUTTER AND DEVICE FOR FORMING
CURVED SLOTS UNDER LIPS OF CON-
TINENTAL TYPE HEELSJohn M. Fuller, Beverly Farms, Mass., as-
signor to Vulcan Corporation, Portsmouth,
Ohio, a corporation of Ohio

Application July 6, 1944, Serial No. 543,672

9 Claims. (Cl. 12—42)

This invention relates to an apparatus for cutting a curved segmental-shaped slot in the breast under the lip of a "continental" type heel.

Heels of this type which usually have a straight breast face and an extension lip thereabove are used to a considerable extent without any slot under the lip, but where a slot has been proposed or used, it has been cut through the side faces of the heel so that it mars the otherwise smooth surfaces of the side faces and makes necessary a considerable finishing operation when the heel is attached to the shoe upper. Such slots also tend to weaken the heel.

The primary object of the present invention is to provide a simple and effective apparatus by which a segmental-shaped slot may be cut under the lip of the heel to a sufficient depth without cutting through the side surfaces or breast edges of the heel.

A further object of the invention is to provide an apparatus for cutting a curved segmental-shaped slot under the lip of a "continental" type heel so that the extremities of this slot are entirely in the breast face of the heel adjacent the breast edges and are not cut through to mar the side faces of the heel.

An important feature of the present invention is the provision of a saucer-shaped or frusto-conical-shaped cutter which may be regarded as a saucer-shaped circular saw which has the proper diameter and slope or angle to fit the curved under surface of a heel lip for cutting a slot across the breast of the heel directly under the lip, the upper wall of the resulting slot being a continuation of the under curved surface of the lip. The apparatus also includes a mounting for the cutter together with an adjustable slide bracket mechanism for holding the heel to be cut and for moving the heel in contact with the cutter at the proper angle and for the correct distance. The slide bracket mechanism includes an inclined slide plate on which is mounted a guided slide for carrying the heel to be cut. The slide is provided with an adjustable stop for limiting its movement toward the cutter and also with adjustable means for positioning the heel on the slide.

Other objects, features and advantages of the apparatus of the present invention will be better understood from the following description of a preferred embodiment thereof, taken in connection with the accompanying drawing in which:

Fig. 1 is a side elevational view of a preferred form of the apparatus constructed in accordance with the present invention.

Fig. 2 is a front view of the apparatus shown in Fig. 1, looking from the left.

Fig. 3 is a broken vertical sectional side view of a portion of the apparatus showing the relationship of the cutter and heel at approximately the completion of the cutting operation.

Fig. 4 is a view taken on the line 4—4 of Fig. 3 with the heel removed from the cutter and showing the shape of the cut in the heel under the lip.

The drawing shows a preferred form of apparatus constructed and arranged in accordance with a preferred form of the invention, but it will be apparent from the following description that considerable variation may be made. Referring to the drawing, the apparatus comprises a supporting bracket 10 mounted on a bench or other suitable fixed support 12. An electric motor 14 is rigidly mounted on the right side of the vertical section of the bracket 10 with its spindle extending vertically, the upper end of which carries a frusto-conical-shaped saw or cutter 16. The saw 16 includes a heavy base mounting section as shown, and an annular outer saw-toothed section or saw blade 18 of the desired thickness, for example, approximately one-sixteenth of an inch. In a particular instance, the saw 16 had a diameter of about three inches, with the blade 18 about three-eighths or one-half inch wide on top and wide enough within the cone to take any heel lip. The slope or angle of the saw blade with respect to the axis of the cutter spindle was approximately the angle shown in Fig. 1 of the drawing. Other types of cutting edges may be used which are adapted to generate a surface of revolution having a conical or frusto-conical-shaped cross-section to fit the heel lip. The left side of the vertical section of the bracket 10 is provided with two spaced guides 20, between which is mounted a vertically-adjustable plate 22 having fixed bracket members 24 cut at the angle indicated. A slide plate 26 is rigidly attached to the brackets 24 and the plate 22 at the angle to the axis of the cutter indicated in Fig. 1, which is the same or substantially the same as that of the saw blade. The vertically-adjustable plate 22 is provided with an adjusting screw 28 threaded in its lower portion, the screw 28 being mounted for rotation in a lug 30 fixed to the lower portion of the bracket 10. The adjusting screw 28 is provided at its lower end with a head below the lug 30 and with a nut 32 above the lug which is keyed to the screw 28. The turning of the screw 28 moves the plate 22 up or down with respect to the cutter 16, as desired. After the height of the

plate 22 is adjusted, it is rigidly secured to the side of the bracket 10 by means of a bolt 34 which extends through a slot in the plate 22. The guides 20, one on each side of the plate 22, insures its vertical movement. The stationary slide plate 26 has a central rounded beveled notch at its upper end so that it fits somewhat around without engaging the spindle of the motor 14, as shown in Fig. 1.

The heel-carrying or mounting portion of the apparatus operates on the slide plate 26 and comprises a relatively wide slide 36 having attached guides 38 which operate along the side edges of the slide plate 26. The slide plate 26 and slide 36 are centered with respect to the spindle of the motor, and the upper end of the slide 36 is provided with a round notch so that it does not come in contact with the spindle of the motor. The upper end of the slide 36 is provided with a bridge-like breast stop 40 which is attached to the slide 36 by screws, as indicated in Fig. 2. The upper left corner of the breast stop 40 is beveled at 41 to receive the breast of a heel 42 to be cut. The central section of the lower front corner of the breast stop 40 is also beveled so that it does not come in engagement with the cutter 16 or its holding nut. In fact, the bridging section of the breast stop is sufficiently high to ride above the cutter, as clearly indicated in Fig. 1. The right side of the slide 36 is provided with a handle 44 which is secured to the slide and the breast stop by means of screws, as shown in Fig. 2.

The heel 42 to be cut by the apparatus is mounted on a wedge-shaped member 46 which is attached to the slide 36 by means of screws, and which is replaceable by wedges having different angles in order to present the heel to the cutter with the under side of the lip at the proper angle with respect to the under side of the cutter. Other means for adjusting the angle of the heel may be used in place of the wedges. A hinged plate with an adjusting screw could be used, or the slide plate 26 could be made adjustable with respect to the plate 22. The heel 42 is held in alignment on the wedge 46 with respect to the axis of the cutter by means of an adjustable heel gage or side stop 48 provided with a slot and an adjusting screw by which it is held firmly to the outer portion of the slide 36. The wedge 46 and the heel gage 48 may be made of wood, while the remainder of the apparatus may be made of steel or other suitable metal. The gage 48 may be made from a rectangular-shaped block with the inner end shaped, as indicated, to fit the upper side face of the particular type of heel to be grooved. The lower inner portion of the gage 48 is preferably cut away as indicated in Fig. 2, so that it extends over the wedge 46.

The slide plate 26 is provided at its lower end with a stop pin 50 for limiting the movement of the slide 36 away from the cutter and to prevent it from sliding off the slide plate 26. The movement of the slide 36 and the heel mounted thereon toward the cutter, is limited by a slide stop 52 having an end flange which contacts the lower end of the slide plate 26. The slide stop 52 is attached to the upper portion of the slide 36 by a screw and washer 54, the screw extending through a slot in the slide stop 52. By properly adjusting the slide stop 52, the slot in the heel may be accurately cut to the proper depth in the face of the heel breast directly under the lip without marring the side faces or breast edges of the heel.

The apparatus is relatively simple to operate,

the heel being held manually in its proper position on the wedge 46 against the end of the gage 48 and the breast stop 40 by the operator's thumb. The operator simply grasps the handle 44 with his right hand and extends his thumb around the heel 42, firmly holds the heel against the gage 48 and the breast stop 40 while moving the slide assembly, including the slide plate 36, forward, so as to bring the heel into cutting relation with the cutter 16. As soon as the slide stop 52 contacts the slide plate 26, the assembly is retracted, the slotted heel removed, another put in its place, and the operation repeated. The apparatus is arranged so that the slide assembly is retracted to the stop pin 50 so that the cutter clears the lip 56 of the heel 42. After the assembly is retracted the heel may be allowed to drop from the slide into a pan or other receptacle. If desired the heel may be held in place by mechanical means and the slide may be automatically reciprocated by suitable means. Also, if desired, the cutter may be reciprocated while the heel is held stationary.

The relative positions of the heel 42 and the cutter 16 at the completion of the slot or groove 58 is shown in Fig. 3 wherein the respective angles of the slide 36, the wedge 46 and the cutter, are shown. It will be noted that the slide 36 is always at a fixed angle with respect to the axis of the cutter, and substantially parallel to the slope of the cutter. The desired angle for a particular heel is obtained by the use of a wedge 46 having the proper adjustment angle. The shape of the slot 58 formed in the heel by the cutter, and the extremities of the cut in the breast face of the heel, are shown in Fig. 4 of the drawing. The upper wall of the slot 58 with the heel upright is desirably and preferably a continuation of the under surface of the lip of the heel which curves upwardly and outwardly from the under center line of the lip.

Having described the invention in its preferred form, what is claimed as new is:

1. An apparatus for cutting the slot in the breast under the lip of a "continental" type heel comprising a rotary cutter having a slot cutting edge constructed and arranged to generate a surface of revolution having a frusto-conical-shaped cross-section substantially fitting the curved under surface of the heel lip, means for mounting a heel to be cut in a position adapted to present the breast of the heel directly under the lip to the edge of the cutter with the lip within said surface of revolution, said means including a reciprocable slide mounted adjacent the cutter on a slide base set substantially parallel to a line through the center of the heel, the axis of the cutter, and said conical surface.

2. An apparatus for cutting a curved slot in the breast under the lip of a "continental" type heel, comprising a cutter having a saw blade with a frusto-conical-shaped cross-section, means for mounting a heel to be cut with the breast of the heel facing the saw, said means including a reciprocable slide on which the heel is mounted, said slide in turn being mounted on a slide base which is adjacent the cutter and which is set at substantially the same angle to the axis of the cutter as that of the saw blade, and adjustable means for limiting the movement of the slide toward the cutter.

3. An apparatus for cutting a slot in the breast under the lip of a "continental" type heel comprising a saw having a blade of frusto-conical shaped cross-section, means for mounting a heel to be cut with the breast of the heel facing the

saw, said means including a reciprocable slide on which the heel is mounted, said slide in turn being mounted on a slide base which is adjacent to the saw and set at substantially the same angle to the axis of the saw as that of the saw blade, and means for setting the heel at the proper angle for cutting the slot under the lip.

4. An apparatus for cutting a slot in the breast under the lip of a "continental" type heel having a lip with a rounded under surface, comprising a rotary cutter having a saw blade with a frusto-conical-shaped cross-section, means for mounting a heel to be cut with the breast and lip of the heel facing the saw, means providing for the relative movement of the cutter and mounting, said mounting means including means for aligning the heel with the axis of the cutter.

5. In an apparatus for cutting a narrow curved slot in the breast under the lip of a "continental" type heel having a lip with a rounded under surface, a rotary cutter having narrow cutting elements constructed and arranged to generate a surface of revolution having a frusto-conical-shaped cross-section.

6. In an apparatus for cutting a narrow slot having curved walls in the breast directly under the lip of a "continental" type heel having a lip with a rounded under surface, a rotary cutter including an annular saw blade having a frusto-conical-shaped cross-section.

7. In a machine for cutting a narrow curved slot in the breast directly under the lip of a "continental" type heel, a rotary cutter having a narrow cutting edge constructed and arranged to generate a surface of revolution having a frusto-conical-shaped cross-section, means for mounting a heel to be cut in a position for presenting the breast face of the heel under the lip to the edge of the cutter with the lip extending within the surface of revolution, means providing for the

relative movement of the cutter and the mounting, and means for controlling the depth of the slot cut in the breast of the heel.

8. In a machine for cutting a narrow curved slot in the breast of a "continental" type heel directly under the curved under surface of the lip of the heel, a rotary cutter having narrow end cutting elements constructed and arranged to generate a narrow path of revolution having a frusto-conical-shaped cross-section, heel mounting means for supporting a heel to be cut in a position for presenting the breast face of the heel under the lip to the edge of the cutter with the lip extending within and adjacent to the surface of revolution, slide means providing for the relative movement of the cutter and the mounting, and means for limiting the extremities of the slot to the breast face of the heel.

9. In an apparatus for cutting a narrow curved slot in the breast of a "continental" type heel directly under the curved surface of the lip of the heel, a rotary cutter having narrow end cutting elements, said cutter being constructed and arranged to generate a narrow path of revolution having a frusto-conical-shaped cross-section, a vertically adjustable slide plate mounted adjacent said cutter at an acute angle to the axis of the cutter which is approximately equal to the angle of said cutting elements, a slide on said slide plate guided for reciprocable movement toward and away from the said cutter, said slide including means for mounting a heel to be slotted, said means including an adjustable member for lining the center line of said heel with the axis of said cutter, a breast stop against which the breast of the heel is held during the cutting operation, and a wedge on said slide on which the heel is mounted for adjusting the angle of the heel lip with respect to the angle of the cutting elements.
